UNITED STATES PATENT OFFICE.

DAVID J. O'NEILL, OF COUNCIL BLUFFS, IOWA.

SHOE.

SPECIFICATION forming part of Letters Patent No. 366,503, dated July 12, 1887.

Application filed May 6, 1887. Serial No. 227,346. (No model.)

To all whom it may concern:

Be it known that I, DAVID J. O'NEILL, a citizen of the United States of America, residing at Council Bluffs, in the county of Pottawattamie and State of Iowa, have invented certain new and useful Improvements in Shoes, of which the following is a specification, reference being had therein to the accompanying drawings.

10 This invention pertains to certain new and useful improvements in shoes; and it consists in the detailed construction, combination, and arrangement of the parts, substantially as hereininafter fully set forth, and particularly pointed out in the claims.

15 In the accompanying drawings, Figure 1 is a plan view of my invention, with the upper portion of the shoe removed. Fig. 2 is a cross-sectional view thereof. Fig. 3 is a view of the 20 sock worn in connection with my invention, and Fig. 4 is a view of the last.

The object of this invention is to provide a 25 shoe having means for retaining the "big toe" of a person's foot apart from the other toes and in a proper natural position, and also to provide a sock to be worn in connection with my improved shoe.

In carrying out my invention I provide a shoe, A, in the forward end of the sole of which 30 is formed a narrow slit, wherein I secure a strip or partition, a, preferably of heavy sole-leather, the same being retained by stitches passing therethrough and through the insole.

In constructing my shoe I employ a last, B, 35 which has a slot or aperture, b, therein for entrance of the strip or partition a in the formation of the shoe. After securing the strip or

partition a in position I place a toe-piece or bridge, b', over the upper end thereof, which at its ends is secured to the sole of the shoe, 40 as shown. The strip or partition can be additionally secured or held in position by stitching the same to the toe-piece or bridge b'.

In Fig. 3 I have shown the form of sock or stocking worn in connection with my invention, which consists in providing the sock C with a mitten-like end, C', having a separate compartment, c, for the big toe of the wearer, thus providing a comfortable fitting sock and shoe for the wearer and effecting the separation of the big toe from the others for the purpose of curing the enlargement of the joint of the foot caused by bunions, corns, &c.

I am aware that it is not new to secure to the inner side of the front part of the sole a 55 wedge-shaped ridge or partition, and hence I do not make broad claim thereto.

I claim as my invention—

1. The herein-described shoe, comprising the sole having a slit or aperture therein, and the 60 strip or partition secured in said aperture, substantially as shown, and for the purpose described.

2. The combination, with the shoe, and the sole having a slit or aperture therein, of the 65 strip or partition secured in said aperture, and the toe-piece or bridge, substantially as shown and described.

In testimony whereof I affix my signature in presence of two witnesses.

DAVID J. O'NEILL.
